UNITED STATES PATENT OFFICE.

JAMES S. DONOHUE, OF GEORGETOWN, DISTRICT OF COLUMBIA, ASSIGNOR OF ONE-HALF TO JAMES W. WHELAN, OF GEORGETOWN, DISTRICT OF COLUMBIA.

GAS-PURIFIER.

SPECIFICATION forming part of Letters Patent No. 695,875, dated March 18, 1902.

Application filed January 2, 1902. Serial No. 88,077. (No model.)

To all whom it may concern:

Be it known that I, JAMES S. DONOHUE, a citizen of the United States, residing at Georgetown, District of Columbia, have invented 5 certain new and useful Improvements in Gas-Purifiers; and I do declare the following to be a full, clear, and exact description of the invention, such as will enable others skilled in the art to which it appertains to make and 10 use the same, reference being had to the accompanying drawings, and to the letters of reference marked thereon, which form a part of this specification.

My invention relates to means for arresting 15 and removing impurities from illuminating and other gases after the gas has passed through the ordinary purifiers; and its object is especially to remove naphthalene from the gas. The means I employ subjects the gas 20 as it comes from the ordinary purifier first to a contact and admixture with a spray of steam, and, second, it causes the gas so treated to pass through benzin or other naphthalene-arresting liquid.

25 The accompanying drawings illustrate my apparatus or system for arresting naphthalene in gas.

In the drawings, Figure 1 is a side elevation, partly in section, of the invention; and 30 Fig. 2 is a plan view of the invention with connecting-pipes.

Referring to the drawings, the letter A indicates a pipe leading from an ordinary purifier and having a valve A'.

35 a is a by-passage, and a' is the outlet.

A pipe B leads from pipe A into a box C and is provided with a valve b. The pipe B enters a vertical chamber D in the box. A steam-atomizer pipe E passes through the upper part of the box C and enters the chamber D. The lower end of this chamber is open and is immersed in a supply of benzin G in the bottom of the box.

40 F is a pipe opening into the box and conveying the gas therefrom, after treatment, into the pipe a' and is provided with a valve f.

I is an opening in the upper part of the box, through which the benzin is poured in and is provided with a tight cap i. An overflow attachment K is provided for the benzin about one and one-half inches above the level of the lower end of the chamber D. A door H, near the bottom of the box, allows entrance to remove the contaminated benzin and to cleanse the box. 55

Arrows mark the course of the gas through my purifier in Fig. 1 and through the by-passage in Fig. 2.

I have found that the introduction of steam may under very favorable conditions be dispensed with, the benzin alone being sufficient to arrest the naphthalene; but the use of the spray with the benzin insures a complete removal of the naphthalene. 60

To use my improvement, open the valves 65 b and f in the pipes B and F and cut off the flow of gas through the by-passage a with the valve A'. Then turn on the spray of steam.

I do not limit myself to the exact location of the opening I or of the door H, as shown 70 in the drawings, as these may be placed in any preferred part of the box.

Having now described my invention and the manner of using it, I claim and desire to secure— 75

In a gas-purifier a box, an opening in the upper part thereof provided with a cover, a door in its side, an overflow attachment, a vertical chamber in the box having an open bottom adapted to be immersed in a naphthalene-arresting liquid, an inflow gas-pipe provided with a valve connecting with said chamber, a steam-pipe opening into said chamber, an outlet-pipe and a by-pass provided with a valve substantially as herein set forth. 80

85 In testimony whereof I affix my signature in presence of two witnesses.

JAMES S. DONOHUE.
